UNITED STATES PATENT OFFICE.

MELVILLE CLARK, OF CHICAGO, ILLINOIS, ASSIGNOR TO MELVILLE CLARK PIANO COMPANY, OF CHICAGO, ILLINOIS, A CORPORATION OF ILLINOIS.

VENT-REGULATOR FOR PNEUMATIC ACTIONS.

1,132,650.

Specification of Letters Patent.

Patented Mar. 23, 1915.

Application filed January 5, 1914. Serial No. 810,300.

To all whom it may concern:

Be it known that I, MELVILLE CLARK, a citizen of the United States, residing at Chicago, in the county of Cook and State of Illinois, have invented new and useful Improvements in Vent-Regulators for Pneumatic Actions, of which the following is a specification, reference being had to the accompanying drawings, forming a part thereof.

10 The purpose of this invention is to provide an improved device for regulating the vent or primary bleeder of a pneumatic action.

15 It consists in the elements and features of construction shown and described as indicated in the claims.

20 In the drawings: Figure 1 is a detail front elevation of a portion of the exhaust chamber of a pneumatic action having its primaries equipped with this invention, the removable cover strip in front of the regulators being partly broken away so as to disclose them. Fig. 2 is a vertical section at the line 2—2 on Fig. 1. Fig. 3 is a detail 25 section at the line, 3—3, on Fig. 2.

This invention is in the drawings shown applied to a familiar form of pneumatic action, in which—

30 1 is the main exhaust chamber containing the primary pneumatics, 2, each of which is mounted upon a duct bar or stick, 3, these duct bars being fixed within the chamber, 1, the upper end of each being connected to a tube, 5, leading to the tracker not shown.

35 For the purpose of venting the primary pneumatic, by what is commonly called the "bleeder", and adapting it for convenient positioning of an adjusting device, a cross port, 7, is formed in each of the duct bars, 40 3, leading from one of the lateral surfaces of the bar into the duct, 3^a, which connects with the primary pneumatic; and from the forward surface of the bar, a hole, 8, is drilled transversely into the cross port.

45 Into this hole, 8, there is set a screw, 9, preferably having its end spheroidal, the head of the screw being exposed at the forward side of the bar so that it can be screwed in

and out to cause it to obstruct more or less the cross port, 7. By this arrangement, it 50 will be seen that easy access is obtainable to all the adjusting screws, 9, for regulating the vent of all the primary pneumatics, and that the duct bars, 3, being of hard wood, and the screws 9, being tightly fitted into 55 the bores, 8, and made to cut their own thread when they are screwed into these bores, the adjustment is secure against accidental change.

I claim:—

1. In a pneumatic action, in combination with an exhaust chamber, a duct bar sustained wholly within such chamber having an air duct for connection with a primary pneumatic to be contained within the chamber and having a cross port leading to the air duct from one surface of said bar which is exposed within said chamber, and a screw set into the bar transversely of said cross port and having its head exposed for adjustment to vary the extent of its intrusion into the cross port. 60

2. In a pneumatic action, in combination with the exhaust chamber, duct bars mounted within said chamber having air ducts for 65 communication with the primary pneumatics, and primary pneumatics connected with said duct bars respectively, the duct bars having each a cross port leading from a lateral surface of the bar which is exposed within the chamber into the air duct; an adjusting screw set into each bar transversely of the cross port from the side of the bar which faces toward the outer wall of the chamber, said outer wall having a 70 removable cover plate whose removal exposes the heads of the adjusting screws for adjustment to vary the extent of their intrusion into the cross ports respectively. 75

In testimony whereof, I have hereunto set 80 my hand at Chicago, Illinois, this 29th day of December, 1913.

MELVILLE CLARK.
